UNITED STATES PATENT OFFICE

2,429,078

REFRIGERANT CONTAINER FOR RAILWAY CARS

Vinton E. Sisson, Chicago, Ill., assignor to Standard Railway Equipment Manufacturing Company, Chicago, Ill., a corporation of Delaware

Application April 2, 1945, Serial No. 586,205

6 Claims. (Cl. 62—17)

1

This invention relates to railway refrigerator cars known as top-bunker refrigerator cars such as disclosed in the Bonsall Patent No. 2,136,999 of November 15, 1938, owned by my assignee, wherein the cooling means, preferably containers for water ice or eutectic ice, are suspended immediately below the roof of the car. The lading is supported in spaced relation to the floor by a foraminous rack. Flues, preferably associated with the side walls of the car, communicate between the space about the refrigerant container and a space between the floor of the car and a floor rack supported thereon. The path of circulation is from the refrigerant compartment downwardly through the aforementioned flues, through the space under the floor rack and upwardly through and about the lading in the lading compartment to the refrigerant compartment.

In certain types of lading, such as frozen foods, and wherein below freezing temperatures must be maintained in the car transporting the same, where water ice is used as the refrigerating medium, approximately thirty pounds of salt is necessary for each one hundred pounds of ice to provide such required temperature. The containers for the ice are usually of the open mesh type and a drip pan is positioned below the containers, which drip pan forms a partition between the refrigerant compartment and the lading compartment and conducts the meltage to the flues. When the salt is added to the ice it quite frequently runs therethrough and through the open meshes of the refrigerant container and on to the drip pan therebelow in such quantities that it seriously retards, if not blocks entirely, the circulation of air to the flues.

The principal object of the invention, therefore, is to provide means to prevent the salt which has been dumped upon the ice through the car hatches from passing through the ice and bottom of the container in an undissolved state and resting upon the drip pan and thereby retarding air circulation, thereby reducing the efficiency of the refrigerating system.

More specifically the object of the invention is to provide a refrigerant container which retains the advantages of the open mesh type of container, but is provided with an imperforate area located immediately below the hatch so that the salt cannot fall therethrough. In an open mesh type of refrigerant container the circulating air contacts the refrigerant directly, thus providing the most efficient transfer of heat from the air to the refrigerant.

2

Other objects and advantages will appear in the following description thereof.

Referring now to the accompanying drawing forming part of this application and wherein 5 like reference characters indicate like parts:

Figure 1 is a diagrammatic plan view of the type of railway refrigerator car to which my improved refrigerant container is applicable.

Figure 2 is a partial cross section of a railway 10 refrigerator car showing my improved refrigerant container and associated parts of the car.

Figure 3 shows my improved refrigerant container in upside down position.

In the drawings 1 shows a portion of a 15 refrigerator car roof having a hatch 2 therethrough and 3 is the upper portion of a side wall of the car. 4 indicates a substantially horizontal partition located below the roof and above the lading compartment 5. The lining 6, spaced from the side wall 3, provides a flue 7 therebetween which 20 communicates with the duct 8 below the refrigerant container 9 located under the hatch 2 through which said container may be serviced. The air warmed by the lading rises and passes 25 through duct 8 and being cooled by the refrigerant in the container descends through the flue 7 to underneath the foraminous floor rack, not shown, and rises through the lading and repeats the cycle, all as shown in Bonsall Patent 30 No. 2,136,999, supra.

Figure 1 shows a typical arrangement diagrammatically in plan view of the relation between the containers and the car proper.

In the servicing of this type of car it is the 35 practice to dump about fifteen hundred pounds of crushed ice in each container and when lower than freezing temperatures are required to be maintained in the lading compartment, about thirty pounds of salt are added for each one hundred

40 pounds of ice. This salt is ordinarily just dumped in on top of the ice and in practice quite frequently a considerable portion of the salt passes through the ice only partially dissolved and through the open meshes of the container 45 bottom and rests upon the partition 4, thereby partially blocking the flow of air in the duct 8. To obviate this difficulty I have found it expedient to prevent the salt from passing through the meshes of the container, and thus the meshes

50 of the container below the hatch are closed by providing an imperforate sheet 10 extending transversely across the bottom of the container and preferably also extending up each side 11 thereof, as clearly shown in Figure 3, which figure 55 is of the container in upside down position for

clarity. Obviously the imperforate plate 10 may be an integral part of the container with the meshing extending from the edges 12 thereof to the ends 13 of the container. Furthermore, the imperforate area of the bottom of the container may be varied according to the dimensions of the hatch and the container and the quantity of salt necessary to maintain the temperature required in the lading compartment.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a railway refrigerator car having a roof provided with a hatch, a wall, a substantially horizontal partition forming with said roof and wall a refrigerating chamber below the hatch and above the lading compartment of the car; a refrigerant container positioned within said chamber below said hatch and spaced above said partition, a flue for conducting air cooled by refrigerant in said container downwardly to the lower part of said lading compartment, the portion of the bottom of the container below said hatch being imperforate and the parts of said bottom adjacent said imperforate portion being foraminous.

2. For use in a refrigerator car having a roof provided with a hatch; a refrigerator container adapted to be positioned below said hatch, the portion of the bottom of the container below said hatch being imperforate and the parts of said bottom adjacent said imperforate portion being foraminous.

3. A refrigerator container for a railway re-

frigerator car having a roof provided with a hatch, said container being of larger dimension than said hatch and adapted to be positioned adjacent the roof and below the hatch and having a bottom and sides and end portions extending upwardly therefrom, the portion of the bottom of said container occurring normally under the hatch being imperforate and the remainder of said bottom being foraminous.

4. A refrigerant container as defined in claim 3 wherein the portions of the sides of the container extending upwardly from the imperforate portion of the bottom are also imperforate.

5. In a refrigerator car having a roof provided with a hatch; a refrigerator container of larger dimension than said hatch positioned below said hatch, the portion of the bottom of the container below the hatch opening being imperforate and the parts of said bottom adjacent said imperforate portion being foraminous.

6. For use in a refrigerator car having a roof provided with a hatch; a refrigerator container adapted to be positioned below said hatch, the portion of the bottom of the container below the hatch being imperforate and the parts of said bottom adjacent said imperforate portion being foraminous, the portions of the sides of the container adjacent the imperforate bottom portion also being imperforate.
